INVENTOR
ROBERT C. SUTTON
BY
Munro & Co.
ATTORNEY

UNITED STATES PATENT OFFICE.

ROBERT CRADDOCK SUTTON, OF WYNCOTE, PENNSYLVANIA.

BED.

Application filed March 3, 1928. Serial No. 258,818.

This invention relates to a bed, the primary object of which is to provide an obstetrical delivery bed designed to assist nature; and the secondary object is to provide 5 a conventional sleeping bed that combines the primary object.

Still another object is to construct a bed that will enable the mother to greatly assist nature in the delivery of a child, whether 10 aided or unaided.

In carrying out the several objects herein above mentioned, the invention is susceptible of modification without departing from the intent and spirit or sacrificing any of 15 the advantages claimed of the invention; there being shown in the drawings, for purposes of illustration, a preferred and practical form, in which;

Figure 1 represents a side elevation of a 20 bed constructed in accordance with this invention;

Fig. 2 is a top plan thereof;

Fig. 3 is a bottom-end elevation, taken from the foot of the bed;

25 Fig. 4 is a longitudinal section taken on the line 4—4 of Fig. 2;

Fig. 5 is a detail perspective view of a portion of the footboard of the bed, showing the mounting of the improved foot rest 30 thereon;

Fig. 6 is a detail vertical section through the footboard and foot rest, and also through a portion of the post showing the means for adjusting the height of the bedstead;

35 Fig. 7 is a detail perspective view of one of the leg supporting members or braces.

Fig. 8 is a perspective view of the foot end of the bed showing the tray attached.

In the embodiment illustrated, a bedstead 40 is shown of the usual construction, including side bars 1 and 2, a headboard 3 carried by upright posts 4 extending some distance above the side bars and provided on their rear faces with hooks 10 for a purpose hereinafter to be described.

A footboard 5 includes end posts 6 similar to the head posts 4; the footboard connecting said posts being arranged in a plane below the side bars 1 and 2 which is shown 50 clearly in Fig. 4. The usual spring 7 is supported by the bedstead and has mounted thereon a mattress 15, preferably made in sections 16 and 17, the latter being shorter than the former and designed to be used at 55 the foot of the bed. The longer section 16 has its upper end raised and supported by

the hooks 10, any suitable means being provided for connection with said hooks. The foot section 17 has a hollowed out or concave upper face arranged preferably at the 60 center thereof, as shown at 18 said recess being here shown tapered toward the center of the bed, and which is designed as a comfortable resting place for the abdomen prior to and during delivery.

65 Mounted on the inner face of the footboard 5 at longitudinally spaced intervals are foot rest supporting bracket plates 8. These plates 8 are provided with a plurality of transversely extending slots 9 to receive the ends of the L-shaped brackets 12. These L-shaped brackets 12 are secured to the lower face of the foot rest 17 which extends across and is adjustably mounted on the footboard 5 by the slots 9 in the plates 70 8 and the engagement therewith of the brackets 11.

Two curved wooden arms 30 and 31 are mounted on the foot posts 6, one being attached to the inner side of one post and the 80 other to the inner side of the other post. These arms are convexly curved as shown and extend laterally toward each other with a proper space between the ends thereof so as to provide a comfortable support and resting place for the lower part of the torso during delivery of the child. The space between the ends is intended to permit of the free and unobstructed passage of the child from the mother. The tray 25 is detachably 85 mounted on these arms and supported by the brace 26 attached to the footboard. This tray is used only during delivery.

These arms constitute an important feature of the bed during childbirth, when the 90 upper part of the body of the female rests face downward on the lower half of the bed with her legs resting on and extending over the arms and her feet resting on the foot rest 13.

100 Two curved rods 14 and 14^a are detachably mounted on the posts 6. These rods 14 and 14^a are slidably mounted in brackets 19 secured to the inner faces of the posts 6 and held in adjusted position therein by 105 set screws 20. The inner ends of these rods are curved as shown at 21 and their terminals are extended substantially at right angles to the body portions thereof being arranged longitudinally of the bed and spaced laterally from each other a sufficient 110 distance to permit the passage between them

- of the child when delivered. These ends 22 have curved plates 23 adjustably mounted thereon, said plates carrying straps 24 designed to encircle the legs of the patient.
5. Mounted in suitable brackets 26 in a plane above the straps 24 and opposite the space between them, is a tray 25 composed of any suitable material, said tray being shown curved upwardly at its rear or outer end 10 and with the bottom plate or wall thereof arranged facing the bed and arranged to receive the child when delivered. This tray may also be used to support instruments and the like when an attendant is present.
15. Eye bolts 27 are carried by the side bars 1 and 2 near the head of the bed and are designed to support hand pulls or grips, not shown, for use by the mother during the delivery of the child.
20. The casters 28 on which the bedstead is mounted are preferably attached through blocks 29 the thickness of which may be varied to vary the height of the bed.

When this bed is to be used as a maternity bed, the mother lies on the mattress 15 face downward with the abdomen disposed in the recess 18, and the legs resting on and extending over the arms 30 and 31 and engaged by the straps 24. The feet may 30 then be placed on the footrest 13 and by pushing on this rest and pulling on the hand straps carried by the eye bolts 27, much suffering is alleviated and nature is greatly assisted in the delivery of the child.

35. When unaided, the child will be delivered onto the tray 25, or when an attendant is present, it may be taken by the attendant and placed thereon or anywhere else.

It will thus be seen that this bed presents 40 substantially the appearance of an ordinary bed and may be used as such, when not intended for delivery purposes, by removing the mattress section 17 and pulling down the section 16 into place. The tray may be readily 45 removed and also the rods 14 and 14^a with the straps carried thereby, and when this has been done, the bed would appear simply as an ordinary sleeping bed and when desired for use for the purpose for 50 which it is intended, it may be readily prepared by reversing the above described operation, replacing the section 17, and the parts to be mounted on the footboard 5, thus readily converting it into a delivery bed.

Without further description it is thought 60 that the features and advantages of the invention will be readily apparent to those skilled in the art, and it will of course be understood that changes in the form, proportion and minor details of construction

may be resorted to, without departing from the spirit of the invention or its scope as claimed.

I claim:—

1. A convertible bed and obstetrical apparatus comprising a bedstead, having a footboard, a foot rest removably mounted on the inner face of said footboard, and leg engaging means detachably mounted on said 70 footboard.

2. A convertible bed and obstetrical apparatus comprising a bedstead having a footboard, a foot rest detachably and adjustably mounted on the inner face of said footboard, 75 leg engaging means carried by said footboard and adjustable toward and away from each other and means located between said leg engaging means in position to receive a child when delivered.

3. A convertible bed and obstetrical apparatus comprising a bedstead having a head and footboard, means on the head board for supporting a mattress at one end and holding it in inclined position, a footrest carried by 85 said footboard and leg engaging means carried by said footboard.

4. A convertible bed and obstetrical apparatus comprising a bedstead having a footboard, a foot rest mounted on said foot board, 90 arms mounted on the footboard at the corners thereof and adjustable toward and away from each other, said arms having their inner ends turned laterally outwardly, leg engaging straps adjustably mounted on 95 said out-turned ends and presser plates carried by said ends.

5. A convertible bed and obstetrical apparatus comprising a bedstead with foot posts and having two arms curved convexly 100 and attached to the inner side of said foot posts and extending laterally towards the center of the bed, with space of proper width between the ends.

6. A bed comprising a bedstead having 105 posts connected by a footboard with a foot rest thereon, and a pair of curved body supporting arms arranged above said connecting board with their ends spaced apart.

7. A bedstead including foot posts, a connector uniting the lower ends of said posts, and longitudinally curved arms secured to 110 said posts and extending toward each other with their ends spaced apart.

8. A bedstead including foot posts, a connector uniting the lower ends of said posts, and longitudinally curved arms secured to 115 said posts and extending toward each other with their approaching ends spaced apart and curved outwardly.

ROBERT CRADDOCK SUTTON.
